SCREW-TOP JAR WRENCH

Charles Escher, Jersey City, N. J.

Application October 18, 1944, Serial No. 559,203

2 Claims. (Cl. 81—3.43)

This invention is a wrench for facilitating the removal of the screw tops of glass jars such as are commonly employed in the home canning of fruits and vegetables. These screw tops often stick so tightly that it is impossible to remove them without the use of tools or until the jar rubbers, with which they are usually associated, are pulled from between the lower edge of the cap and the glass seat of the jar.

Wrenches of various kinds, including band wrenches, have been heretofore used to loosen such screw tops, but none of them has appeared to meet practical requirements of price, efficiency and ease of operation.

The object of the present invention is to provide a jar wrench of the band type, so constituted that it will be economical to manufacture, light, durable, easy to manipulate and highly effective in use. These objects are primarily accomplished through the employment of the novel handle construction hereinafter more fully described and claimed.

Features of the invention, other than those adverted to, will be apparent from the herein-after detailed description and claims when read in conjunction with the accompanying drawing.

The accompanying drawing illustrates one practical embodiment of the invention, but the construction therein shown is to be understood as illustrative, only, and not as defining the limits of the invention.

Figure 1 is a perspective view showing the upper portion of a jar with a screw cap thereon and a wrench embodying the present invention positioned to remove the cap.

Figure 2 is a plan view of the assembly shown in Figure 1, but with the handle and part of the band in section.

Figure 3 is a face view of the handle.

Figure 4 is a section through the handle on the line 4—4 of Figure 3.

Figure 5 is a diagrammatic view showing the mode of operation of the wrench in gripping the screw top of a jar.

The handle 1 of the wrench of the present invention is preferably made of heavy gauge sheet metal blanked out from flat stock and then manipulated by dies into the form shown in the drawing. In its finished form it embodies an angle plate having parallel portions 2 and 3 which are flat and these are joined to one another by a sloping portion 4. Along both sides and across one end of the angle plate are formed flanges 5 to impart strength and rigidity to the

angle plate and provide an appropriate grip for the hand of the operator.

The portion 3 of the angle plate is cut out to provide two spaced apart openings 6 and 7 which are separated from one another to form a transverse bar 8 and around this bar one end of the band 9 is looped, as at 10, so as to be returned upon itself and secured by a rivet 11 which serves to firmly anchor that end of the band to the bar 8. The other end of the band 9 is adapted to be passed through the cut out opening 7 and is provided at longitudinally spaced apart distances with perforations 12 adapted to be engaged with a post 13, forming a continuation of and rigid with the inclined or sloping portion 4 of the angle plate.

I call particular attention to the fact that the opening 6 is spaced some little distance from the end of the portion 3, so as to provide, at the in-board end of the handle, a projecting nose 14, the outer edge of which is adapted to contact with the outer periphery of a conventional screw top T of a jar J.

The importance of this projecting nose 14 will more clearly appear from Figure 5. In this figure I have shown a circle T' which indicates the outer periphery of the screw top. The heavy line 1' in this figure indicates the axis of the handle 1 along which are indicated three points 14', 8' and 13'. The point 14' designates the extreme edge of the nose 14. The point 8' indicates the bar 8 forming the anchor of one end of the band 9 and the point 13' corresponds to the post 13 and indicates the anchorage of the other end of the band.

When the parts are initially positioned in co-operative relation with the jar top, the handle is placed at approximately the angle shown in Figure 5, so that when the handle is moved in the direction of the arrow a, indicated in this figure, the handle will form a compound lever. In the first place it will be rocked on the fulcrum 8'. This will tend to cause the point 14' to move in the direction of the arrow b along the surface of the circle T', while the point 13' will move in the direction of arrow d to take up the slack in the band 9. As soon as this slack is taken up and the band is pulled tight, two distinct operations will simultaneously become effective: The first will be the result of the operation of a lever of the second class pivoted at 8' and extending to the outer end of the power arm, indicated at c, with the load at 13', to tighten the band. At the same time the handle will operate as a lever of the first class, the same being fulcrumed at 8' with the power

arm extending from 8' to c and the work arm from 8' to 14'. As the power arm of such lever is of a length greatly in excess of the work arm, great power will be exerted to continue the travel of the point 14' in the direction of the arrow b and this movement will force the points 8' and 13' further away from the circle T' as the handle 1' approaches radial relation with said circle. This forcing of the points 8' and 13' in an outward direction will set up a strong pull upon the band 9 10 and this pull will place the band under such tension that it will be impossible for it to slip with respect to the surface T'. Consequently through the compound leverage to which I have referred, there will not only be a tightening of the band by a pull longitudinally thereof, but there will also be a contemporaneous tightening of the band through radial pressure at the two spaced apart points 8' and 13' in its length. It is this compound leverage and resulting dual tightening effect that is responsible for the unusually tight grip which the band exerts upon the jar top and this result is achieved by the projecting nose 14 of the structure shown in the other figures.

It will of course be understood that several perforations 12 in the band are to permit of use of the wrench with screw caps of different sizes and that an appropriate perforation will be brought into cooperative relation with the post 13 to bring about the relation which I have described.

Having thus fully described the invention, what I claim as new and desire to secure by Letters Patent is:

1. A screw top jar wrench comprising a handle having an outer end portion constituting a hand grip and an inner end portion provided with a pair of spaced apart openings forming between them a transversely extending attaching bar, a post rigid with the handle and extending into the opening which is contiguous to the hand grip, and a band attached at one end to said bar with

its other end normally free and unattached and provided with longitudinally spaced apart perforations adapted for selective engagement with said post, the opening at the other side of the bar being spaced from the inner end of the handle to form a nose extending parallel to said attaching bar and adapted to engage with the outer surface of a jar top when the band is wrapped about the jar top and engaged with said post, whereby said nose will force said bar and post in a direction away from the center of the jar top as the handle is moved from non-radial to substantially radial relation to said jar top.

2. A screw top jar wrench comprising a handle 15 in the form of an angle plate having parallel inner and outer portions connected by a sloping intermediate portion and provided around two of its longitudinal edges and across its outer end with a flange to strengthen said angle plate, the 20 outer end portion of such handle plate and associated flange constituting a hand grip and the inner end portion of said angle plate being provided with a pair of spaced apart openings forming between them a transversely extending attaching bar, a post rigid with the handle and extending into the opening which is contiguous to the hand grip, and a band attached at one end to said bar with its other end normally free and unattached and provided with longitudinally spaced 25 apart perforations adapted for selective engagement with said post, the opening at the other side of the bar being spaced from the inner end of the handle to form a nose extending parallel to said attaching bar and adapted to engage with the 30 outer surface of a jar top when the band is wrapped about the jar top and engaged with said post, whereby said nose will force said bar and post in a direction away from the center of the jar as the handle is moved from non-radial to substantially radial relation to said jar top.

CHARLES ESCHER.
